UNITED STATES PATENT OFFICE.

GEORGE W. BLAKE, OF NEW YORK, N. Y., ASSIGNOR TO JOHN T. KELLY
AND GEORGE M. JONES, OF PITTSBURG, PENNSYLVANIA.

STEAM-RADIATOR.

SPECIFICATION forming part of Letters Patent No. 224,181, dated February 3, 1880.

Application filed July 11, 1879.

To all whom it may concern:

Be it known that I, GEORGE W. BLAKE, of the city and State of New York, have invented a new and useful Improvement in Steam-Radiators; and I do hereby declare that the following is a full, clear, and exact description of the same, reference being had to the accompanying drawing, forming part of this specification.

10 This invention relates to that class of steam-radiators in which interior circulation-tubes are employed. Such tubes have heretofore been made of ordinary gas-tubing, and have had screw-threads cut on one end to screw into 15 tapped holes provided for their reception in the base or trunk of the radiator.

The object of my invention is to reduce the cost of these tubes; and to this end it consists in making them of sheet metal by rolling up 20 strips of such metal into tubular form without uniting the edges, and driving the tubes thus formed into holes provided for them in the base or trunk, thus not only greatly reducing the first cost of the tubes themselves, but avoiding 25 the expense of cutting screws on them and of tapping the holes provided in the base or trunk for their reception.

A is the base or trunk. B B are the radiating-tubes, and C C are the circulation-tubes.

30 The circulating-tubes are made of ordinary sheet-iron, which may be of the cheapest kind, and which, first, is cut into strips of a width corresponding with the intended circumference of the tubes, and then rolled up transversely into tubular form, the edges being just brought together. The tube thus formed, though made much thinner and having a longitudinal slit or opening-seam, *a*, is as good 35 for the purpose as a welded tube, as it is sub-

ject to uniform pressure within and without, 40 and any slight leak through the slit *a* left between the abutting longitudinal edges of the piece of metal of which the tube is made is unimportant. The holes *b b*, provided in the base, for the reception of these tubes are simply 45 drilled and the tubes are driven in very tight. The tubes may be a trifle larger than the holes before entering, especially as the edges of their slits or open seams will generally be left somewhat rough in the cutting of the strips of which 50 they are made, so that a slight contraction of the circumference by the bringing of the edges closer together may take place in the act of driving, and the slight elasticity of the metal will cause the tubes to press outward against 55 the holes and keep themselves tight and firm in their places.

To facilitate the entry of the tubes in driving they may be slightly beveled off at the edges of the end which enters the hole; or 60 the entry of the tubes may be facilitated by very slightly countersinking or tapering the mouth of the hole.

Tubes thus made and applied to a radiator cost about one-sixth as much as welded tubes 65 screwed into tapped holes.

I claim—

The circulation-tubes C, made with a longitudinal slit or open seam, in combination with the radiator base or trunk A, provided with 70 holes *b b*, into which the said tubes are driven and by which they are supported independently of the outer tubes, substantially as herein described.

GEO. W. BLAKE.
